UNITED STATES PATENT OFFICE.

MERRITT GALLY, OF BROOKLYN, NEW YORK.

TELEPHONIC REPEATER.

No. 817,761.

Specification of Letters Patent.

Patented April 17, 1906.

Application filed April 14, 1904. Serial No. 203,165.

To all whom it may concern:

Be it known that I, MERRITT GALLY, a citizen of the United States, residing at Brooklyn, in the county of Kings and State of New York, have invented certain new and useful Improvements in Telephonic Repeaters, of which the following is a specification.

In endeavoring to repeat telephonic messages from one telephone-line to another telephone-line it has been customary to use two receiving-magnets, two diaphragms, and two retransmitting devices—one of each for each of the two lines. In my Patents Nos. 749,481, 751,845, and 753,257 I use only one diaphragm operated upon by a compound receiving-magnet doubly wound, the two wires of the winding to connect one with one of the telephone-lines and the other with the other telephone-line. In my present invention I use only one retransmitting device and having only one diaphragm, but operate magnetically upon this one diaphragm D with two separate receiving-magnets M M', one distinct magnet for each of the two telephone-lines L L' and L' L². A cup n of carbon-granules with button-electrode and the coacting diaphragm D constitute the one retransmitting device common to both lines. Each main line L L' and L' L² has its own receiving-magnet M M', respectively, and its own transmitting induction-coil I I', respectively. Two batteries B and B' and two corresponding primary circuits d' and d² are shown. I prefer to use two primary circuits for the following reasons: First, when the main lines differ much in length two distinct batteries are much better than one, as they can then be adapted each to the requirements of its own main line, and, secondly, this aids in adapting the several parts of each side of the instrument to its particular part of the work of this double repeater.

When the induction-coils I I' are used with separate batteries, the unison of the two sides of the double repeater is secured by the single diaphragm and single retransmitting device acting for both primary circuits simultaneously. I use independent inductive means, as C C, separate from the receiving-magnets and the induction-coils of the primary circuits and having two wires inductively related one to the other, one wire primary to the other, and vice versa, both ends of one of the wires connecting with the line L L' and both ends of the other wire connecting with the line L² L³, this induc-

tion means C C serving to pass a portion of the original message from line to line and aiding in holding the two lines in unity of action, although the single diaphragm actuated by both lines may be used without coil C C, as 60 said single diaphragm serves to preserve unity as heretofore stated. To further hold the two lines L L' and L² L³ in harmony of action, I find it advantageous to connect the two lines for a light constant current, the connections N N' N² N³ of lines L L' L² L³, respectively, having in them resistances, as R R' R² R³, making them of high enough resistance to always shunt sufficient current through both sides of the repeater to secure its full repeating action. These resistances I preferably make of graphite and clay mixed. These resistances are much better than resistance-coils, as they are not disturbed by induction.

I find under some conditions that it is well 75 to have a constant electric current passing through the line while in use, this current being independent of the telephonic electric pulsations. This is especially desirable to provide for the leakages on the line and to minimize the effects of noises and disturbing indications on the passing message. For this purpose I apply electric energy between the resistances R R' and R² R³ to the wires connecting one of the main lines to the other main line. Batteries B² and B³ are shown for this purpose.

In the drawings, P P' represent the two independent permanent magnets for independent connection separately each with its own 90 main line. Their electromagnet pole-pieces are turned at right angles at their ends to both project toward the single diaphragm D as near as possible to its center.

The primary circuit d' leads from battery B to the retransmitter n D and through the induction-coil I. The primary circuit d² leads from battery B' to the retransmitter n D and through induction-coil I'.

The circuits and operation of the repeating devices are as follows: The main-line wire L enters through binder x' and continues to and through magnet M, and on leaving said magnet passes down to and through the outer winding of induction-coil I, then out at left thereof, down to and entering independent induction-coil C C, and continuing through one winding thereof and emerging at bottom of left of said coil and passing up to binder x and so to main line-wire L'. The upper 130

wire of battery B enters through a binder and continues upward by d' until it enters the conductive metallic arm E, which holds in place and is conductively connected with the cup-electrode n , containing carbon-granules, through all which the circuit connects to the button-electrode and passes from thence to the left by wire up and around and then down into the left of primary induction-coil I, passing through the primary winding of said coil and out at left and over to binder, and thus into lower pole of battery B. The circuits of the main line L L' and battery B' primary are the exact counterpart in the right half of the apparatus to the circuits just described for main line L L' and battery B primary of the left half.

In operation a telephonic impulse on main line L L' energizes magnet M, thereby moving diaphragm D and changing the conductivity of the granules in cup n and varying the primary current of battery B' and circuit d' , thus causing a reenergized repetition to main line L L' by the induction from primary circuit d' of coil I' to its secondary winding, which secondary winding is a part of circuit of main line L L' . The same original impulse on main line L L' and its action on magnet M and retransmitter $\approx$ D cause a variation in primary circuit d' similar to the variation in primary circuit d^2 , the said variation of d' causing a reenergized repetition of the original impulse of L L' on itself, and this reenergized repeated impulse, together with the original impulse, induces over to main line L L' through induction-coil C C, thus adding to the repeated impulse caused by n D through primary circuit d^2 and induction-coil I'. This backward repeating to the main line, which started original impulse, causes a repeated upbuilding in rotation of action as just described, constituting a most important means to the results attained.

As the rapidity of electric waves and travel is so infinitely great compared to the rapidity of acoustic vibrations, the above-described upbuilding rotation of telephonic impulse cannot confuse or distort the acoustic transmission, but does build up and amplify each and every acoustic wave.

What I claim as my invention, and desire to secure by Letters Patent, is—

1. In a telephone-repeater for repeating telephonic pulsations from one telephone-line to another telephone-line; a single receiving-diaphragm; and two independent receiving-magnets, both magnets on one side of said diaphragm and to operate said single diaphragm, one of the magnets for connection with one telephone-line, and the other magnet for connection with the other telephone-line.

2. In a telephone-repeater for repeating telephonic pulsations from one telephone-

line to another telephone-line; a single diaphragm; and two independent magnets on one side of said diaphragm and for operating said single diaphragm; energizing-coils for the magnets; the energizing-coil of one of the magnets for connection with one of the telephone-lines and the energizing-coil of the other magnet for connection with the other telephone-line.

3. In a telephonic repeater; a single diaphragm; two independent magnets, one for one telephone-line and the other for another telephone-line; a retransmitting device; and two retransmitting induction-coils, one induction-coil for each of the two telephone-lines.

4. In a telephone-repeater for repeating telephonic pulsations from one telephone-line to another telephone-line; means for receiving the pulsations for both of the telephone-lines; retransmitting means for repeating the telephone pulsations from one of the telephone-lines to the other telephone-line; and an independent induction-coil having two wires establishing inductive relations between the two telephone-lines; one of the wires of the coil to connect with one of the telephone-lines and the other wire to connect with the other telephone-line.

5. In combination with a repeating device for repeating telephonic pulsations from one telephone-line to another telephone-line; connection between the two telephone-lines for passing a constant current from one line to the other; the resistance being great enough to shunt sufficient current through the repeater for its operation.

6. In a repeating device for repeating telephonic pulsations from one telephone-line to another telephone-line; a diaphragm; two independent receiving-magnets, both magnets to operate the same diaphragm; an induction-coil of two wires, one wire to connect with one of the telephone-lines, and the other wire to connect with the other telephone-line.

7. In a repeating device for repeating telephonic impulses from one telephone-lines to another telephone-line; a diaphragm; two independent receiving-magnets, both magnets to operate the same diaphragm; an induction-coil consisting of a core and two coiled wires, one of the wires as primary to the other wire and vice versa, one wire to connect with one of the telephone-lines and the other wire to connect with the other telephone-line.

8. In combination with a repeating device for repeating telephonic impulses from one telephone-line to another telephone-line, a connection between the two telephone-lines; and an electric generator for passing an independent electric current through the two connected lines, and from one to the other.

9. In combination with a repeating device

for repeating telephonic impulses from one telephone-line to another telephone-line; connection between the two telephone-lines; and in said connection an electric generator 5 for passing an independent current from one line to the other and through the lines; and resistance in the connection great enough to

shunt sufficient of the pulsating current through the repeater for its repeating operation.
